[57] CLAIM

The ornamental design for a wall rack for hair dryer, as shown and described.

DESCRIPTION

FIG. 1 is a perspective view of a wall rack for hair dryer showing my new design;

FIG. 2 is a front elevational view thereof;

FIG. 3 is a left side elevational view thereof;

FIG. 4 is a right side elevational view thereof;

FIG. 5 is a bottom view thereof; and,

FIG. 6 is a top view thereof.

The rear of the invention is not ornamented.

The broken line showing of a hand-held hair dryer and power cord is for illustrative purposes only and forms no part of the claimed design.
